UNITED STATES PATENT OFFICE.

JOHN HARMON, OF CHICAGO, ILLINOIS.

CONVEYER.

SPECIFICATION forming part of Letters Patent No. 726,286, dated April 28, 1903.

Application filed November 15, 1902. Serial No. 131,552. (No model.)

To all whom it may concern:

Be it known that I, JOHN HARMON, a citizen of the United States, residing at Chicago, in the county of Cook and State of Illinois, 5 have invented certain new and useful Improvements in Conveyers; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates particularly to an apparatus for raising building materials during the construction of buildings; and the object of the invention is to form an improved device which may be adjusted at various heights to deliver the bricks and mortar accordingly.

It includes a stationary frame and a vertically-movable extension thereon, together with an endless chain and buckets to carry 25 up the material.

In the accompanying drawings, Figure 1 is a side elevation of the apparatus. Fig. 2 is a front elevation thereof.

Referring specifically to the drawings, 30 indicates vertical timbers, and 7 inclined timbers rising from a base-frame 8 and joined at the top, forming the fixed frame or tower. The timbers are suitably braced and joined.

The conveyer comprises a pair of endless 35 chains 9, which pass over sprockets 10 on a shaft 10^a at the bottom of the inclined timbers of the tower. The shaft is geared up to a crank 11 to operate the conveyer. The chains carry buckets 9^a, suitable for brick 40 and mortar, and these buckets slide on ways or guides formed of a pair of rails 12, supported by cross-pieces 12^a between the chains. The purpose of the guides is to prevent sag of the loaded chains.

45 To vary the height of the tower, an extension is used, comprising timbers 13, which slide against the vertical timbers 6 within keepers 6^a. These timbers are raised and lowered by pinions 14 on crank-shaft 14^a at the top of the tower, which engage racks 13^a on the inside of the timbers 13. The racks

are sunken to let the faces of the vertical timbers come together. The extension-timbers 13 are fixed at the adjusted height by bolts 13^b through said timbers and timbers 6, 55 and the latter have a series of bolt-holes 6^b to receive the bolts at different heights. Said extension-timbers also carry the chute 15, hinged thereto, into which the material is dumped from the buckets and which may 60 conveniently be entered into a window or other opening in a wall or allowed to project over a wall being built. The extension-timbers 13 have at the top a shaft 16, with sprockets 16^a, around which the chains pass, 65 and the vertical frames 6 of the fixed tower have near the top thereof a similar shaft and sprockets 6^c, over which the chains pass in their downward run.

The guides and chains are formed in sections or pieces and may be lengthened or shortened by adding or removing sections, as desired. The cross-pieces 12^a can be shifted to bring the guides to the proper inclination, according to the inclination of the upward 75 run of the chains produced by raising or lowering the extensions, and for the lowest height the conveyer-chains may be taken off the top sprockets 16^a and run around the sprockets 6^c only. 80

It will be understood that the adjustment does not have to be changed very often—say a change for every story of the building. In operation the conveyer is stood up beside a building and put to use in a manner evident 85 from the above description. The chute is hinged, as stated, and hung by ropes 15^a, whereby its inclination may be varied.

The reason for having the three sets of sprocket-wheels at respectively the top and 90 bottom of the tower and the top of the extension is to give the chains a triangular run, so that the descending buckets will not interfere with the top of the fixed tower, as they would if the chains were bent over the 95 lower sprockets at the foot of the tower and the sprockets at the top of the extension only.

What I claim is—

1. A conveyer comprising a stationary 100 frame having belt-wheels at the top and bottom thereof, and a movable frame, having

belt-wheels at the top thereof, extensible vertically from the top of the stationary frame, and endless conveyer-chains passing around said wheels, substantially as described.

5 2. The combination with the stationary inclined frame having sprockets at top and bottom, and the vertical frame extensible therefrom, having sprockets and a chute at the top, of the endless carrier-chains passing around

10 said sprockets, having a triangular run, substantially as described.

In testimony whereof I affix my signature in presence of two witnesses.

JOHN HARMON.
